THOMAS KRAEMER, OF PHILADELPHIA, PENNSYLVANIA, ASSIGNOR TO HAWTHORNE & SHEBLE MANUFACTURING COMPANY, OF PHILADELPHIA, PENNSYLVANIA, A CORPORATION OF PENNSYLVANIA.

TALKING-MACHINE MECHANISM.

No. 913,828.

Specification of Letters Patent. Patented March 2, 1909.

Application filed June 3, 1908. Serial No. 436,475.

To all whom it may concern:

Be it known that I, THOMAS KRAEMER, a citizen of the United States, residing at Philadelphia, in the county of Philadelphia and State of Pennsylvania, have invented a certain new and useful Improvement in Talking-Machine Mechanism, of which the following is a specification.

This invention relates to talking machines and is directed to the provision of improved means for controlling the rotation of the record, whereby such rotation may be started and stopped and its speed regulated as desired.

15 In the operation of talking machines, it is important that the record be rotated at just the proper speed, since when rotated at any other speed the tone of the reproduction is not so good, and also since rotation at 20 greater than the proper speed causes excessive wear upon the record. I have, therefore, provided means by which the speed of rotation of the record may be predetermined, and with this an adjustable stop device is 25 combined, which may be moved to any desired position with reference to a scale and which arrests the movement of the part which is operated to regulate the speed of rotation of the record.

30 In accordance with the invention, a starting and speed-regulating lever is provided upon the motor-box of the machine and arranged to move relatively to a scale, by reference to which the lever may be moved 35 to a position which has been found to give the desired speed. An adjustable stop device is arranged in the path of this lever, so that when the speed desired for a reproduction has been found, the stop device may be 40 so positioned that it will arrest the lever in this position and thus permit of moving the lever rapidly to the desired position without referring to the scale.

I have illustrated the preferred embodiment of my invention in the accompanying drawing, in which—

Figure 1 is a view in elevation of a talking machine broken away in part; Fig. 2 is a top view of a portion of the machine, having the 50 motor-box broken away in part to show the governing mechanism; Fig. 3 is a side view of a portion of the machine with the casing similarly broken away; and Fig. 4 is a detail view hereinafter referred to.

55 Referring to these drawings, 1 indicates

the motor-box of the machine, within which is a spring-motor driving a vertical shaft 2 which carries the turn-table of the machine. The disk record 4 is adapted to rest upon the turn-table 3 and to rotate therewith. Extending outwardly and upwardly from the box 1, is a coupling member 5 having an opening through the upper end thereof, and a horn 6 is supported upon the upper end of the member 5 with the opening therethrough in 60 communication with the opening through the member. A tubular tone-arm 7 is pivotally mounted upon the member 5 so as to swing on both vertical and horizontal pivots, and the opening through this arm is also in 65 communication with the opening through the member 5. The sound-box 8 is secured to the free end of the tone-arm 7, with its stylus 9 tracking in the groove in the record 4.

70 The spring-motor within the box 1 is of any suitable construction, and therefore I have not considered it necessary to illustrate it. By means of suitable gearing, the spring of the motor is arranged to drive the shaft 2, 80 and a governing mechanism is employed for regulating the speed at which this shaft is driven. This governing mechanism includes a shaft 10 driven by the spring-motor and having two collars 11 and 12 thereon, the former being secured to the shaft and the latter being loose thereon. These two collars are connected by leaf-springs 13, on each of which is secured a governing weight 14. To the loose collar 12, is secured a 90 brake-disk 15, and brakes 16 are adapted to be moved into and out of contact with one face of this disk. The brakes 16 are secured to a pivotally mounted shaft 17 on the upper end of which is a cam-arm 18. A pin 19 acts with the arm 18, this pin being carried by a crank 20 secured upon a shaft 21 which is mounted for rotation in the frame 30 of the motor and which extends upwardly through an opening in the top of the motor-box. 100 The brakes 16 are connected by a spring 22 to a stationary part of the frame, this spring acting upon the brakes in a direction to draw them away from the disk 15, thus turning shaft 17 in a direction to hold the arm 18 in engagement with the pin 19.

105 On the upper end of the shaft 21, is a starting and speed-regulating lever 23, the end of which is provided with a handle 24. A strip 25 is secured at its ends upon the top 110

of the motor-box and is bent adjacent to its ends to provide a space between it and the top of the motor-box, in which the lever 23 may move. Strip 25 is curved in an arc of a circle about the shaft 21 as a center. On the upper face of the strip are scale markings, as shown in Fig. 2, by reference to which the lever 23 may be moved to the position which will give the desired tone of reproduction. 10 Coacting with the lever 23, is an adjustable stopping device for arresting the movement of the lever. Strip 25 is provided with a longitudinal slot to receive a screw 26, the head of which lies below the strip 25 and the shank of which extends upwardly through the slot and into a threaded opening in a stud 27. A washer 28 of rubber or other suitable material may be provided between the screw and the stud and the head 26 of the 15 screw may have a raised portion 29 thereon entering the slot in the strip 25 to prevent the screw from turning as stud 27 is turned. 20 As thus constructed, it will be seen that by turning the lever 23 to the right in Fig. 2, shaft 21 is turned and carries with it, the crank 20; the shape of the cam 18 is such that when the pin 19 is carried to the right in this way, the cam, shaft 17 and the brakes 16 may turn, actuated by the spring 22, in a 25 direction to carry the brakes 16 away from the disk 15. When this is done, the motor is free to rotate. As the speed of the motor increases, the weights 14 will move outwardly under centrifugal force and thus draw the 30 collar 12 and disk 15 toward the fixed collar 11, and if this movement carries the disk 15 into contact with the brakes 16, the increase in the speed of the motor will be checked. 35 In this way, the speed of rotation of the 40 motor depends upon the position to which the lever 23 is moved, and the strip 25 may be marked off to a scale, by reference to which any desired speed of rotation of the disk may be obtained. After this desired

speed has been found, the stop device may be so positioned that lever 23 may be again moved to this position without the necessity of referring to the scale on the strip 25. Thus by turning the stud 27 to loosen the screw 26, the screw and stud may be moved along upon the strip 25 until the head of the screw is in contact with the lever 23, whereupon the stud 27 may be again tightened. Then after the reproduction has been concluded and the lever 23 moved back to the position in which it is shown in Fig. 2 in order to stop the motor, the lever may be moved back to the position in which it was, without referring to scale upon the strip 25, by merely moving it into engagement with the head of the screw 26. 45 50 55 60

Having now described my invention, what I claim as new therein and desire to secure by Letters Patent is as follows:—

Talking machine mechanism comprising 65 the combination of a rotary support for a sound-record, a motor for rotating the support, a box inclosing the motor, a governing mechanism for the motor, means coacting therewith for starting and stopping and regulating the speed of rotation of the motor, a lever pivotally mounted upon the exterior of the box for the motor and arranged to actuate said means, a strip secured at its ends to the motor-box and overlying said lever, said strip having a slot therein and being provided with scale-markings adjacent to the slot, and a stop device for said lever adjustable along said strip and consisting of a screw 80 extending through said slot and a member threaded on the screw, substantially as set forth.

This specification signed and witnessed this 22nd day of May, 1908.

THOMAS KRAEMER
